UNITED STATES PATENT OFFICE.

WALTER EDWARD IRVING, OF GLENBROOK, CONNECTICUT.

BRACKET FOR STAIR-TREADS.

1,304,056.

Specification of Letters Patent.

Patented May 20, 1919.

Application filed June 25, 1918. Serial No. 241,761.

To all whom it may concern:

Be it known that I, WALTER E. IRVING, a citizen of the United States of America, residing at Glenbrook, county of Fairfield,

5 State of Connecticut, have invented certain new and useful Improvements in Brackets for Stair-Treads, of which the following is a specification.

10 My invention relates to means for conveniently supporting the ends of iron gratings such as are used for making stair treads in ships and other structures. Such stair treads have heretofore generally been made of ordinary rods, which have been inserted 15 in holes in the staircase side members and upset or otherwise fastened therein, but now more highly organized forms of gratings are being used for such stair treads and the question of how best to support these small panels of grating structure from the side members of the staircase is a more difficult one. I 20 have invented a simple form of integral bracket which can be cheaply made without special tools, bent and punched cold, and 25 which forms a most effective support and fastening means for the grating ends. The best form of apparatus at present known to me embodying my invention is illustrated in the accompanying sheet of drawings in 30 which—

Figure 1 is a perspective view of the bracket and one end of a stair tread grating, supported thereby, parts being broken away.

Fig. 2 is a vertical section on line 2—2 of 35 Fig. 1, showing two of the brackets in position on a staircase side support.

Fig. 3 is a detail cross section showing a modified form of bracket.

Fig. 4 is a view similar to Fig. 1, showing 40 the modified construction also illustrated in Fig. 3, and

Fig. 5 is a view similar to Fig. 2, further illustrating said construction shown in Fig. 3.

45 Throughout the drawings like reference characters indicate like parts. The tread grating is composed of horizontally extending, straight bearing members 1, 1, which are held together and spaced apart by bent strips 2, 2, riveted thereto. 3, represents the inclined side supporting member of a staircase to which the bracket body 4, is fastened as by rivets 9, 9.

50 The bracket has end ears 5, 5, bent at right angles to body 4, and spaced to embrace the ends of the outer members 1, 1, of the grat-

ing. Bracket ears and grating members have holes punched in them which register one with another so that the parts may be fastened together by rivets 6, 6. Lugs 7, 7, 60 are formed on the inner surface of the bracket by stamping out and bending in tongues of the body metal, which lugs or tongues come under the ends of certain of the inner straight supporting members 1, 1, 65 of the grating. The holes 8, 8, left by bending out the material to form the lugs conduce to ease in cleaning the parts of the completed stairway and avoiding the collection of dirt in the corners between lugs, bracket 70 bodies, and grating bars, the side member 3 of the staircase having registering openings 12, 12, punched therein, as indicated in Fig. 2.

75 Preferably these lugs are punched out in grooved or curved form as shown so that the grooves or concavities so formed on their upper surfaces will embrace and engage the under edges of bars 1, 1, thus insuring the continued centering of the member 1, on the 80 lugs even under application of great weights which might tend to bend the bars to one side.

85 The rivet holes 6, 6, in end ears 5, 5, register with the holes punched in bars or bearing members 1, to receive rivets 11, 11, which are employed to fasten the bent strips 2, 2, to the bearing members, so that no special punch work is required for this connection.

90 A modified form of grating supporting lug having many advantages is shown in detail in Fig. 3. The punch which forms the opening 8, and stamps out lug 17, is given a special construction so that said lug is grooved or slotted at its upper end, as shown 95 at 10, and is bent through an angle of only about 45 degrees so as to leave it standing in the inclined position shown in Fig. 3. The bearing members 1, of the grating are then seated in grooves or slots 10. This gives a 100 positive, interlocking joint between grating and bracket, and the less degree of flexure of the lug 17, leaves it stronger than the more bent form 7, shown in Figs. 1 and 2.

105 The bracket can be cut and punched at one operation and made very economically in quantity in standard sizes fitting standard sizes of grating panels, and these can be used in the making of any type of iron staircase or ladder.

Having described my invention, I claim:

1. As a new article of manufacture an in-

tegral bracket for supporting stair tread gratings and the like, comprising a strip of metal perforated for reception of means to attach it to a proper support, having perforated ears at either end bent at right angles to the body of the bracket, and supporting lugs formed of tongues of metal stamped out of the body of the bracket and projecting from the same side thereof as do the above mentioned ears.

2. A structure such as set forth in claim 1 in which the lugs are grooved so as to present a concave upper bearing surface.

3. The combination with a grating having 15 a series of horizontally extending members, the outer ones being horizontally perforated near their ends, of a bracket for supporting said grating, comprising a strip of metal having at each end ears projecting at right 20 angles to the bracket body, spaced to embrace the ends of the outer grating members,

and perforated to register with the perforations in said members, and also having lugs punched out of the bracket body and extending under and in contact with the ends 25 of other horizontally extending members of the grating.

4. A combination such as set forth in claim 3 in which the lugs are grooved to partly surround the grating members with 30 which they engage.

5. As a new article of manufacture a bracket for supporting the end of a grating or similar structure which bracket comprises a strip of metal adapted to be fastened to a 35 supporting structure and having a lug stamped out and projecting inwardly toward the grating in an inclined position, said lug having a relatively deep and narrow groove in its upper surface.

WALTER EDWARD IRVING.
